UNITED STATES PATENT OFFICE.

BIRD FITZPATRICK JR., OF PENSACOLA, FLORIDA.

AUTOMATIC DRAFT-CONTROLLING DEVICE FOR ENGINES.

1,111,450.

Specification of Letters Patent. Patented Sept. 22, 1914.

Application filed April 27, 1914. Serial No. 834,741.

To all whom it may concern:

Be it known that I, BIRD FITZPATRICK, Jr., a citizen of the United States, residing at Pensacola, in the county of Escambia and State of Florida, have invented certain new and useful Improvements in Automatic Draft-Controlling Devices for Engines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in automatic draft controlling devices for engines, especially adapted for locomotives, and the object in view is to produce a simple and efficient device of this nature to prevent unnecessary blowing off of steam through the safety or pop valve of the engine.

My invention comprises a simple and efficient device of this nature having various details of construction, combinations and arrangements of parts which will be herein-after fully described, shown in the accompanying drawings and then specifically defined in the appended claim.

I illustrate my invention in the accompanying drawings, in which:

Figure 1 is a view in elevation showing the application of the device to an engine. Fig. 2 is an enlarged detail sectional view through an automatically operated valve controlled by pressure of the steam, and Fig. 3 is an enlarged detail sectional view through a part of the apparatus which allows air to enter the apparatus to pass to the stack of the locomotive to destroy the suction or draft therein.

Reference now being had to the details of the drawings by letter, A designates a valve chamber having an inlet opening B therein, which is adapted to be connected to a boiler, affording means whereby the steam may enter the valve casing. C is an exit opening leading from the valve chamber and through which steam is allowed to pass through the pipe D and communicate with the cylinder F. Said valve casing A is divided by a diagonally disposed partition A' into two compartments, designated respectively by letters A² and A³, and said partition is provided with an opening A⁴, the edge of which

is beveled, and H designates a valve adapted to be normally held seated against the beveled edge of the opening A⁴ through the medium of the spring I which bears against the washer I' engaging a shoulder K upon the stem K'. Said stem K' is provided with a beveled valve K² adapted to seat against the beveled edge of the opening A⁹ formed in the upper end of the valve casing A. A casing L surrounds said spring and an adjusting nut N has a central opening through which said stem K' passes and an adjusting cap O, interiorly threaded, engages the threads of said nut and serves as a means whereby, when the cap is turned in one direction or the other, the nut N may be caused to regulate the tension upon the spring I to adapt the apparatus to operate under varying steam pressure. A vent L' is formed in the casing and through which the steam within the latter may exhaust to the atmosphere after the valve H has seated.

The cylinder F has a piston M mounted therein, provided with a stem M', and a coiled spring Q is mounted about said piston and bears intermediate the inner face of the piston and the end M², which latter is apertured for the reception of the bearing plug P. Said cylinder has a chamber R attached thereto and one end R' of said air chamber is provided with an opening having a plug R² through which the stem T passes, which stem has an integral valve T' thereon. One end R³ of the air chamber is provided with an opening having a beveled seat R⁴ against which the valve T' is normally held by means of the spring S.

A casing W is bolted or otherwise fastened to the air chamber and is provided with series of perforations W' through which air is adapted to enter and the end of the casing W has a plug X, apertured for the reception of the stem T, as shown clearly in Fig. 3 of the drawings.

Leading laterally from the air chamber is a duct R⁶, the ends of which are flanged and apertured as at R⁸ for the reception of fastening means whereby the flange may be fastened to the side of a fire box. A lug F' projects from the cylinder F and is apertured for the reception of fastening means which coöperate with those passing through the aperture R⁸ to securely hold the device to the smoke box. The duct R⁶ leads to the smoke box through which air is allowed to pass to the stack of the engine where it

makes exit and serves to lessen the draft of the furnace, thereby checking the fire and reducing the pressure of the steam.

In practice, it is preferable to adjust the tension of the spring I so that the valve H, actuated thereby, will operate at about a pound less pressure than would be the pressure required to automatically operate the pop or blow off valve of the engine. In operation, therefore, when the pressure of steam in the boiler reaches a degree substantially a pound less than that required to operate the blow-off valve, the valve H will unseat allowing the steam to pass from the chamber A² to the chamber A³ and thence through the pipe which communicates with the interior of the cylinder F and, acting upon the piston M, will cause the same to move against the tension of the spring Q. The stem M' of said piston M, coming in contact with the end of the stem T, will impart a longitudinal movement thereto and cause the valve T' to unseat, allowing air to be drawn through the perforations of the casing W, through the opening X into the air chamber R and thence through the duct R' to be carried through the smoke box to the smoke stack of the locomotive where it makes exit and serves to destroy the suction force, causing excessive draft and thereby putting a damper upon the fire of the engine and in turn lessening the pressure of the steam.

When the pressure reduces to a certain degree to allow the valve H to seat under tension of the spring bearing against the same, the spring S will cause the valve T' to seat, thus shutting off the supply of air and the spring Q will return the piston M to its normal position. Any exhaust steam remaining in the cylinder or in the pipe connecting the same and the chamber A³ will escape through the opening A⁶ and thence through the vent L' to the atmosphere.

From the foregoing, it will be noted that, by the provision of a device made in accord-

ance with my invention, an automatic means is provided whereby the draft of the engine may be controlled and which will tend to save fuel and water and prevent the engine from blowing off steam while idle when standing still or when drifting on grades. The apparatus will also enable engineers to keep a good fire in the engines without the safety valves operating under excessive pressure and will prevent a blow back through the fire door.

What I claim to be new is:

An automatic draft regulating apparatus for engines comprising a valve casing with an apertured partition therein, a valve within said casing, the wall of the latter having an aperture, a portion of the stem of said valve being beveled to seat against the marginal edge of the opening in the casing, an adjusting nut upon said valve-stem, a spring interposed between the nut and the shoulder upon the stem, a cap having threaded connection with said adjusting nut, a cylinder, a pipe communicating between the same and one of the compartments of said valve casing, a piston within said cylinder, a stem to said piston, a spring bearing between the piston and the end of the cylinder, an air chamber with an opening in one end thereof, a valve regulating said opening into the air chamber, a stem upon the air-regulating valve positioned in the path of the piston stem, a perforated chamber, the wall of which is fastened to the air chamber and through which the stem of the air-regulating valve passes, a spring adapted to seat the latter, and a pipe communicating with the air chamber and adapted to convey air to the stack of an engine.

In testimony whereof I hereunto affix my signature in presence of two witnesses.

BIRD FITZPATRICK, Jr.
